UNITED STATES PATENT OFFICE.

DAVID WELSH, OF TOLEDO, OHIO.

MOISTENER.

1,280,603.

Specification of Letters Patent. Patented Oct. 1, 1918.

Application filed June 14, 1918. Serial No. 239,984.

To all whom it may concern:

Be it known that I, DAVID WELSH, a citizen of the United States, residing at Toledo, in the county of Lucas and State of Ohio, 5 have invented new and useful Improvements in Moisteners, of which the following is a specification.

Persons whose calling or profession requires the counting of sheets, cards, tickets 10 or the like, and who are so situated that a sponge cup or such like device is not available for moistening the thumb or forefinger to cause an adhesion therebetween and the sheets being counted, not infrequently resort to the unclean and unsanitary method 15 of placing their thumb or finger in their mouths to moisten the same.

It is the purpose of the present invention to produce a simple contrivance which may 20 be readily secured upon the clothing of the user whereby moisture may be applied to the thumb or finger by simply drawing the finger or thumb over the face of the device.

It is a further object of the invention to 25 produce a moistener in the nature of a hollow casing having an opening on the outer face thereof the wall of which being flared inwardly. In the casing is arranged a sponge. The casing, at the top thereof being provided with an aperture whereby 30 water may be admitted to moisten the sponge. The casing, upon the rear thereof having means whereby the same may be attached to the belt or to the clothing of the 35 user.

Other objects and advantages will appear as the nature of the invention is better understood, reference being had to the accompanying drawings, in which,

40 Figure 1 is a perspective view illustrating the application of the improvement.

Fig. 2 is a substantially vertical longitudinal sectional view through the same.

Fig. 3 is a transverse sectional view approximately on the line 3—3 of Fig. 2.

The device is primarily adapted for use by railway conductors. The improvement, however, is not to be restricted in use in this particular, as the same will be found effective in any class of profession or labor requiring the counting of tickets or sheets, and especially so when the person making such counts performs his duty in a place or

at a location where an ordinary sponge-cup cannot be conveniently used.

55 The device comprises a substantially rectangular hollow casing 5, the upper and outer corner of which being rounded as at 6. The outer face of the casing is provided with a round opening and the wall surrounding the opening is flared inwardly, as at 7. Through the opening is inserted a sponge 8, and water may be delivered to the sponge through the opening. Preferably, however, I provide the top of the casing with an aperture 9 and through this aperture water is delivered to moisten the sponge.

60 On the back of the casing is arranged a loop 10 through which the plate of the conductor is passed, but it is to be understood, 70 and it is also illustrated by the dotted lines in Figs. 2 and 3 of the drawing, that in lieu of the loop a spring catch or pin may be employed. This permits of the device being attached to any desired portion of the 75 clothing of the user.

From the foregoing description it is believed the simplicity and advantages of the construction will be apparent. The user merely draws his finger or thumb over the 80 outer face of the casing in a line with the opening therein. The finger contacts with the sponge or other absorbent element and is moistened. The finger travels freely over the round upper corner of the casing, 85 and tickets or similar articles may be readily counted without resorting to the unsanitary method of placing the finger or thumb in the mouth of the counter.

Having thus described the invention, what 90 I claim is:

1. A finger moistener adapted to be attached to the person of the user, comprising a closed hollow casing having an opening in the outer face thereof, an inwardly flared 95 wall surrounding the opening, and a moistened sponge in the casing.

2. A finger moistening device adapted to be attached to the clothing of the user, comprising a closed substantially rectangular hollow casing, the upper and outer corner of which being rounded, the outer face of the casing having an opening, an inwardly flared wall surrounding the opening and an absorbent element in the casing.

100 105 3. A finger moistening device adapted to

be attached to the clothes of the user, comprising a closed hollow rectangular casing, the upper and outer corner of which being round and the upper edge of which having 5 an opening, said casing on its outer face having a round opening, the wall surrounding said opening being flared inwardly, an ab-

sorbent element in the casing and disposed opposite the round opening, and a loop on the back of the casing adapted to receive a 10 belt whereby the casing may be attached to the user.

In testimony whereof I affix my signature.
DAVID WELSH.
